UNITED STATES PATENT OFFICE.

HARRY A. DEITERS, OF SPENCER, WEST VIRGINIA, ASSIGNOR OF ONE-HALF
TO OTTO BARTH, OF COOLVILLE, OHIO.

WRENCH.

SPECIFICATION forming part of Letters Patent No. 634,661, dated October 10, 1899.

Application filed August 4, 1899. Serial No. 726,176. (No model.)

To all whom it may concern:

Be it known that I, HARRY A. DEITERS, a citizen of the United States, residing at Spencer, in the county of Roane and State of West Virginia, have invented a new and useful Wrench, of which the following is a specification.

The invention relates to improvements in wrenches.

10 The object of the present invention is to improve the construction of pipe and nut wrenches and to provide a simple, strong, and durable one capable of being readily operated to adjust it to pipes, nuts, and other objects and adapted to grip the same firmly with a pressure coextensive with the resistance of such object, so that there will be no liability of the same slipping between the jaws.

15 The invention consists in the construction and novel combination and arrangement of parts hereinafter fully described, illustrated in the accompanying drawings, and pointed out in the claims hereto appended.

20 In the drawings, Figure 1 is a perspective view of a wrench constructed in accordance with this invention. Fig. 2 is a longitudinal sectional view of the same. Fig. 3 is a transverse sectional view on line 3 3 of Fig. 2.

25 Like numerals of reference designate corresponding parts in all the figures of the drawings.

1 designates a fixed or rigid jaw provided with a short shank 2, coöperating with a sliding or movable jaw 3 and having its shank 35 bifurcated at 4 to receive a bar or handle 5, which operates as a lever and which is connected with the movable jaw. The fixed jaw 1 extends from one side of the shank 2, and the lever or handle 5 is provided with a laterally-extending head 6, forming an eccentric and provided with a curved slot 7, which receives a pivot 8, whereby the lever is connected with and is adapted to actuate the movable jaw 3. The lever is fulcrumed at 40 the inner end of the head on a pivot or pin 9, which passes through the bifurcation 4 of the shank 2. The movable jaw 3 is connected with the shank 2 of the fixed jaw 1 by a substantially U-shaped yoke 10, conforming to 45 the configuration of the said shank 2, and composed of parallel sides and a rear connecting portion which is arranged on the back of

the shank of the fixed jaw 1. The nut or other object to be engaged by the wrench is placed between the two jaws, and by forcing 55 the lever forward the jaws are carried into engagement with such nut, which is firmly gripped, and the greater the resistance offered by the nut or other object the greater will be 60 the clamping action of the jaws.

The head which extends laterally from the lever forms one arm of the same, and the body of the lever, which forms the other arm, by being much longer than the head enables the lever to exert a powerful gripping action. 65

70 The jaws 1 and 3 are provided with toothed or serrated engaging faces formed by removable plates 11 and 12, having dovetailed grooves 13 and 14 interlocked with corresponding tongues of the jaws. These plates are adapted to be readily removed, so that a set having straight faces, like those shown in the drawings, for engaging flat surfaces may be employed, or plates having curved faces for engaging rounded surfaces may be substituted for the same to adapt the wrench for operating on pipes and rods. 75

75 It will be seen that the wrench is exceedingly simple and inexpensive in construction, that it possesses great strength and durability, and that it is capable of firmly gripping an object and of being readily adjusted to the same. It will also be apparent that the pressure exerted on the nut or other object operates to force the jaws into engagement 80 with the same.

85 What is claimed is—

90 A wrench comprising a fixed jaw having a straight shank with a rear bifurcated end, a movable jaw slidingly connected to the said shank of the fixed jaw, a lever fulcrumed in the rear bifurcated end of the said shank and having a head with a curved slot therein, and a fastening device extending through the rear end of the sliding jaw and the end slot 95 of the head of the lever.

95 In testimony that I claim the foregoing as my own I have hereto affixed my signature in the presence of two witnesses.

HARRY A. DEITERS.
